UNITED STATES PATENT OFFICE.

ALBERT TAYLOR, OF HENRYVILLE, INDIANA.

DESIGN FOR A RADIO-RECEIVING-SET CABINET.

Application filed March 13, 1928. Serial No. 25,824. Term of patent 3½ years.

To all whom it may concern:

Be it known that I, ALBERT TAYLOR, a citizen of the United States, and a resident of Henryville, in the county of Clark and State of Indiana, have invented a new, original, and ornamental Design for a Radio-Receiving-Set Cabinet, of which the following is a specification, reference being had to the accompanying drawing, forming part thereof.

Figure 1 is a perspective view of a radio receiving set cabinet, showing my new design.

Figure 2 is a top plan thereof.

I claim:

The ornamental design for a radio receiving set cabinet, as shown.

ALBERT TAYLOR.
